UNITED STATES PATENT OFFICE.

SAMUEL S. FRETZ AND FRANK C. YEAGLEY, OF PHILADELPHIA, PENNSYLVANIA, ASSIGNORS TO S. S. FRETZ MANUFACTURING COMPANY, A CORPORATION OF PENNSYLVANIA.

UMBRELLA-RIB.

SPECIFICATION forming part of Letters Patent No. 782,231, dated February 14, 1905.

Application filed June 6, 1904. Serial No. 211,230.

To all whom it may concern:

Be it known that we, SAMUEL S. FRETZ and FRANK C. YEAGLEY, citizens of the United States, residing in the city and county of Philadelphia, State of Pennsylvania, have invented a new and useful Improvement in Umbrella-Ribs, of which the following is a specification.

Our invention consists of an umbrella-rib having means interposed between the sides of an end portion thereof for reinforcing said portion and vastly increasing the strength and durability thereof.

Figures 1 and 2 represent views of opposite sides of the end portion of an umbrella-rib embodying our invention. Fig. 3 represents a section thereof on line *xx*, Fig. 2. Fig. 4 represents a section on line *yy*, Fig. 2.

Similar letters of reference indicate corresponding parts in the figures.

Referring to the drawings, A designates an umbrella-rib, and B designates a plurality of side members with eyes at the tip end thereof, which, excepting the features of our invention applied thereto, are of usual construction. Interposed between said side members is the reinforce C, the same consisting of a crimp or trough pressed out of or struck up from the metal of the rib and extending in the longitudinal direction thereof, said crimp or trough forming a plurality of pieces or leaves of the metal of the rib between the eyes and having openings therein registering with the pivot-receiving openings of said eyes, said side members and crimp being pressed together, thus reducing the thickness

of the same, producing practically a rib with a four-ply end of integral construction.

It will be seen that there is a plurality of pieces or leaves between the side members and integral with the body of the rib, whereby the end of the rib is vastly strengthened and its durability correspondingly increased.

Various changes may be made in the details of construction shown without departing from the general spirit of our invention, and we do not, therefore, desire to be limited in each case to the same.

Having thus described our invention, what we claim as new, and desire to secure by Letters Patent, is—

1. In an umbrella-rib of the character stated, a reinforce for an end portion thereof, composed of leaves which are interposed between the sides of said portion and integral with the same.

2. An umbrella-rib having a four-ply tip end composed of side members and a plurality of leaves intermediate of said members, said members and leaves having registering eyes therein and said members and leaves being integral.

3. An umbrella-rib having a four-ply end composed of side members and leaves intermediate thereof, said members and leaves being integral.

SAMUEL S. FRETZ.
FRANK C. YEAGLEY.
